(57) **CLAIM**

We claim the ornamental design for a portable computer, as shown and described.

DESCRIPTION

FIG. 1 is a front perspective view of a portable computer of the present invention;

FIG. 2 is a rear perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof;

FIG. 8 is a bottom view thereof;

FIG. 9 is another front perspective view thereof; and,

FIG. 10 is another front perspective view thereof.

The broken lines in the drawings illustrate portions of the portable computer that form no part of the claimed design. The broken lines in FIGS. 9 and 10 represent environmental subject matter only and form no part of the claimed design.

1 Claim, 10 Drawing Sheets
